UNITED STATES PATENT OFFICE.

WILLIAM DIETER, OF NEWARK, NEW JERSEY.

AIR-LEAK VENT FOR TORPEDOES.

Application filed August 4, 1922. Serial No. 579,667.

To all whom it may concern:

Be it known that I, WILLIAM DIETER, a citizen of the United States of America, residing in Newark, in the county of Essex 5 and State of New Jersey, have invented certain new and useful Improvements in Air-Leak Vents for Torpedoes, of which the following is a specification.

In automobile torpedoes it is common to 10 provide two receptacles, one for alcohol or other fuel, and the other for water, with means for feeding these liquids to the heating apparatus or superheater after the torpedo has been launched. It is customary 15 to construct these liquid compartments or receptacles closely adjacent the head of the air flask, for compactness, but this involves the difficulty that if any leakage of compressed air from the flask occurs, 20 it enters the communicating liquid receptacle and must be discharged therefrom to avoid its generating an air pressure therein which would expel the liquid to the superheater. For this purpose it is common 25 to provide a vent for conducting away any slow leakage entering either or both receptacles when the torpedo is stored prior to launching. Means are provided whereby upon launching, or in preparation therefor, 30 such leak vent is shut off, so that the receptacles are hermetically sealed and pressure may be introduced into them for expelling the liquids at the desired rate in the course of the run of the torpedo.

35 A suitable apparatus for such purpose is set forth in Patent No. 1,022,486, to F. M. Leavitt, and in Patent No. 1,125,979, to W. Dieter. An improved construction is set forth in my application Serial No. 540,912, 40 filed March 3, 1922.

In any such venting means the best location for the outlet for air from the liquid receptacle or compartment is at the top thereof, and in the medial vertical plane 45 when the torpedo lies trim or level. Difficulty is, however, encountered because of the rolling or pitching of the torpedo boat or other vessel carrying the torpedoes before launching. Such vessels are usually of 50 light draft, and subject to serious rolling and pitching. If the torpedoes are stored in a fore and aft position, the rolling of the vessel equally rolls the torpedo, and this rolling may often be so great as to submerge 55 the open end of the vent tube, so that any leakage results in expelling liquid

from the compartment. If the torpedoes are stored transversely, the rolling has less effect, but the pitching of the vessel is accompanied by an equal roll of the torpedoes. 60 The present invention aims to provide means whereby the vent outlet tube will always remain in free communication with the air space in the top of the liquid compartment, notwithstanding that the rolling 65 is such as would submerge such outlet vent.

To this end the present invention provides for enclosing the outlet of the vent tube within a chamber having through perforations or the like, a restricted communication with the interior of the compartment, adapted in case of rolling and submergence, to retard the entry of liquid into such chamber so as to leave the vent outlet in communication with the air space 75 therein, the latter being in communication with the air space in the compartment. Thus, when rolling occurs, a small amount of liquid enters the chamber, and upon the reverse roll this is discharged so as to 80 free the chamber preparatory to the next submergence.

The preferred embodiment of the invention is illustrated in the accompanying drawings, wherein:

Figure 1 is a vertical longitudinal mid-section of the mid-portion of a torpedo showing the liquid compartments and the venting means and related apparatus, the portions of which exterior to the compartments are rearranged in diagrammatic manner.

Fig. 2 is a longitudinal vertical mid-section of the chamber enclosing the vent outlet.

Fig. 3 is a transverse section thereof on the line 3-3 in Fig. 2.

Fig. 4 is a transverse section on the line 4-4 in Fig. 1, on a scale intermediate that of Figs. 1 and 2, showing three positions 100 of the cylinder during rolling.

Fig. 5 is a transverse section corresponding to Fig. 3, and showing a modified construction.

To enable the mechanism shown in Fig. 1 to be understood, I will briefly describe it, making reference to said patents and application for a more detailed description.

Referring first to Figure 1, A indicates the shell or hull of the torpedo and B the reservoir or flask of compressed air. From this flask an outlet pipe *a* leads to a pres-

sure reducing valve C by which the air pressure in the flask is reduced to a lower and uniform pressure. From the low pressure side of this valve leads a pipe b which 5 extends to the heater or superheater D, and from the latter a pipe c leads to the engine (not shown) which is commonly a turbine, and by which the screw propellers are driven in the well-known manner. At some 10 suitable point in the pipe or passage a is introduced a starting valve E which may be of any known construction, and whereby the air is admitted to the heater and engine at the instant of launching the torpedo.

15 Within a strong container F is provided the usual enclosure for the water and liquid fuel. This is commonly formed by extending the air flask B rearwardly in the form of a cylindrical wall d having a flange to 20 which is securely attached a disk or head e. A chamber G formed within this container F is sub-divided into two compartments by a partition H of comparatively thin metal, such as metal sheet or plate, which is pref- 25 erably constructed in the form of an annular vessel having a central opening for the free passage through it of the pipe a and which is supported within the container F in any suitable manner, as by brackets f. 30 The partition or vessel H thus divides the chamber G into two compartments, an outer compartment I, and an inner compartment J. In the construction shown the outer compartment I is designed to hold water 35 and the inner compartment J to hold alcohol or other combustible fluid; but this arrangement may be reversed by suitably altering the respective pipe connections which will be described.

40 In the reduced pressure pipe b is formed a slight contraction or choking g, and between this and the reducing valve C a branch h leads to a valve shell i where the duct branches and leads to two valves K and 45 L. From the valve K a pipe k leads to the fuel tank or compartment J. From the valve L a pipe l leads into the water space or compartment I. From the bottom of the fuel compartment J there leads a pipe j in 50 which is introduced a check valve M, and which pipe j leads thence to a fuel nozzle m through which fuel is sprayed or otherwise introduced into the heater. From the bottom of the water compartment I leads a pipe p in 55 which is introduced a check valve P, whence the pipe p extends to the heater D and terminates in a spray nozzle q for introducing water. The valves K, L, M, P, have the functions described in said Leavitt Patent 60 No. 1,022,486.

For preventing any slight leakage at the joints x or x' into the water compartment I generating a pressure in the latter, means are provided for venting off any such air pressure from this compartment. The vent-

ing means here shown is the same as that set forth in my said prior application. A vent tube 5 passing through the rear wall or flange 6 leads from its open end 7 forming the vent outlet, to a vent valve Q which is normally open and permits outflow through a tube 8 into suitable connection with the conduit h, whence the air may escape freely through b, D, c, into the afterbody. The valve Q is open at all times after air pressure is stored in the air flask, and until the torpedo is being prepared for firing. For the purposes of the present invention the valve Q may be treated as an open passage between tubes 5 and 8.

According to the present invention, instead of the outlet 7 into the vent tube 5 being in open communication with the air space at the top of the compartment I, it is enclosed in a chamber 30 preferably cylindrical in form and arranged longitudinally, as shown in Fig. 1. It is preferably constructed, as shown in Figs. 2 and 3, of an outer cylindrical casing 31, an inner cylindrical casing 32, and end heads 33, these three parts being united by their adjoining end flanges being soldered or otherwise joined together. This construction affords a middle chamber 34 surrounded by an annular space 35. The chamber 34 is crossed at its middle by a transverse tube 36. In the preferred construction the structure has at its bottom five (more or less) perforations 37, and between the chambers 34 and 35 communication through a bottom perforation 38, and a middle perforation 39 formed in the top of the cross-tube 36: and the annular space 35 communicates on opposite sides through perforations 40. 40 with the exterior.

In the normal trim position air may flow through any of these perforations into the inner chamber 34, and thence out through the outlet 7. In case of rolling, so as to submerge more or less the casing 30, water may enter the outer chamber 35 through the bottom perforations 37 and the lowermost lateral perforation 40; but the air outlet is maintained through the upper unsubmerged perforation 40, and thence through the tube 36 and perforation 39 to the inner chamber. The water entering the outer space 35 can flow only very slowly into the inner chamber 34 through the perforation 38, so that it would require a long time for this inner chamber to so far fill with water as to cut off the flow of air from 40 to 39, and in rolling, the duration or phase is too short to permit any considerable inflow of water, because the perforation 38 is so small as to permit water to enter only very slowly. On the reverse roll the casing 30 is for the greater part of the time out of water, and during this period there is a rapid outflow through the five perfora- 125 130

tions 37, and a slower outflow through the one perforation 38, but the flow through the latter is sufficiently fast to discharge all of the water from the chamber 34 before the roll has gone far enough to resubmerge the casing on the opposite side. Consequently, during the middle portion of each roll the chamber 34 is emptied of any water that entered it during the submergence at the end of the roll. The purpose of the perforation 38 is to afford a simple means for thus purging the inner chamber of water; of course, an inlet check valve could be used for this purpose, but the perforation accomplishes all needful purpose with greater simplicity.

Fig. 4 shows in full lines the positions in case of an abnormal roll which, without the present invention, would submerge the vent outlet 7; it shows in dotted lines the mid or trim position, and also the position of extreme roll to the opposite side.

It will be understood that the structure provided by the present invention may be greatly modified so long as its essential features are retained. What is essential is that the outlet 7 shall communicate with an enclosed chamber of sufficient capacity to be partly filled with water and yet maintain an air space with which the outlet 7 is in communication, and it is desirable that such perforations or openings shall be provided as shall during partial submergence of the structure maintain free communication between this air space and the air space above the level of water in the compartment. To attain this, provision is made for restricting the inflow of water to the chamber while preventing a sufficiently rapid outflow therefrom to purge it between the extreme rolling positions. The construction preferably includes a tortuous or indirect passage afforded by the annular chamber 35. The capacities and the areas of the perforations are such that the water enters space 35 with a restricted flow, and enters therefrom into the chamber 34 with a still more restricted flow, so that, considering the brief period of submergence of the vent structure, the water level in 35 is lower than in the compartment I, and that in the inner chamber 34 is lower than that in the space 35.

Fig. 5 illustrates one of numerous modifications in which the structure shown in Fig. 3 is modified by multiplying the annular space 35. To this end an outer jacket 41 is provided, thus forming an annular space 42 around the annular space 35. Similar perforations are provided, as in the cylindrical shell 31.

In this specification, wherever the term "perforation" or "perforations" is used, the singular is to include the plural, and vice versa; it being immaterial how many

perforations are employed, provided their areas are correctly proportioned to accomplish the stated results.

The proportions are such that in rolling the vent structure might be wholly submerged during extreme rolling movements without admitting sufficient water to the inner chamber 34 to submerge the outlet 7. The rolling would have to amount to practically 90° before sufficient water could enter to fill the chamber 34 and permit water to flow out through 7; and a much less degree of rolling exceeds that which is possible in practice.

If in the torpedo boat the torpedoes are stored athwartships, then the rolling of the boat simply throws the water endwise of the torpedo, and as it cannot enter at either end of the chamber 34, and can only leak in through the perforations 37 and 38, it has not time to enter fast enough to carry any material amount of water into the chamber 34, so that the vent outlet 7 cannot become submerged.

What is claimed is:

1. In a torpedo having a liquid compartment and means for venting gaseous pressure therefrom having a vent outlet at the normally upper part of such compartment, the combination therewith of means for excluding liquid from said outlet in case of such rolling of the torpedo as would submerge such outlet, comprising a chamber communicating with said outlet having restricted communication with the compartment.

2. In a torpedo having a liquid compartment and means for venting gaseous pressure therefrom having a vent outlet at the normally upper part of such compartment, the combination therewith of means for excluding liquid from said outlet in case of such rolling of the torpedo as would submerge such outlet, comprising a chamber communicating with said outlet and a circuitous passage between said chamber and the compartment affording restricted communication between the chamber and compartment.

3. In a torpedo having a liquid compartment and means for venting gaseous pressure therefrom having a vent outlet at the normally upper part of such compartment, the combination therewith of means for excluding liquid from said outlet in case of such rolling of the torpedo as would submerge such outlet, comprising a chamber communicating with said outlet and a circuitous passage surrounding said chamber and affording restricted communication between the chamber and compartment.

4. In a torpedo having a liquid compartment and means for venting gaseous pressure therefrom having a vent outlet at the normally upper part of such compartment,

- the combination therewith of means for excluding liquid from said outlet in case of such rolling of the torpedo as would submerge such outlet, comprising a chamber in free communication with the outlet, and having restricted communication on opposite sides with the compartment.
5. In a torpedo having a liquid compartment and means for venting gaseous pressure therefrom having a vent outlet at the normally upper part of such compartment, the combination therewith of means for excluding liquid from said outlet in case of such rolling of the torpedo as would submerge such outlet, comprising a cylindrical shell forming a chamber in free communication with the outlet, and having restricted communication on opposite sides with the compartment.
10. 6. In a torpedo having a liquid compartment and means for venting gaseous pressure therefrom having a vent outlet at the normally upper part of such compartment, the combination therewith of means for excluding liquid from said outlet in case of such rolling of the torpedo as would sub-
15. 7. In a torpedo having a liquid compartment and means for venting gaseous pressure therefrom having a vent outlet at the normally upper part of such compartment, the combination therewith of means for excluding liquid from said outlet in case of such rolling of the torpedo as would submerge such outlet, comprising a cylindrical shell forming a chamber in free communication with the outlet, and an enclosing shell forming an intervening annular space, 30 with perforations affording restricted communication between said space and chamber, and between said space and the compartment.
20. 8. In a torpedo having a liquid compartment and means for venting gaseous pressure therefrom having a vent outlet at the normally upper part of such compartment, the combination therewith of means for excluding liquid from said outlet in case of such rolling of the torpedo as would sub-
25. 9. In a torpedo having a liquid compartment and means for venting gaseous pressure therefrom having a vent outlet at the normally upper part of such compartment, the combination therewith of means for excluding liquid from said outlet in case of such rolling of the torpedo as would sub-

merge such outlet, comprising a cylindrical shell forming a chamber in free communication with the outlet, and an enclosing shell forming an intervening annular space, 30 with perforations affording restricted communication between said space and chamber, and between said space and the compartment.

35. 10. In a torpedo having a liquid compartment and means for venting gaseous pressure therefrom having a vent outlet at the normally upper part of such compartment, the combination therewith of means for excluding liquid from said outlet in case of such rolling of the torpedo as would submerge such outlet, comprising a cylindrical shell forming a chamber in free communication with the outlet, and an enclosing shell forming an intervening annular space, 40 with a transverse tube, and perforations affording restricted communication between said space and the compartment, and from said space through said tube to the chamber.

45. In witness whereof, I have hereunto signed my name.

WILLIAM DIETER.
